Primary Examiner — Cary M Robinson*Assistant Examiner* — Michelle Devlin(57) CLAIM

The ornamental design for a display screen with a graphical user interface for a vehicle, as shown and described.

DESCRIPTION

The sole FIGURE is one embodiment of a display screen with a graphical user interface for a vehicle.

Any broken line, which shows the display screen, any text elements, symbols, and any portions of the graphical user interface, forms no part of the claimed design.

1 Claim, 1 Drawing Sheet
